UNITED STATES PATENT OFFICE.

EKKO SOLLMANN, OF HOBOKEN, NEW JERSEY, ASSIGNOR TO THE GEO. BORGFELDT & COMPANY, OF NEW YORK, N. Y.

ELECTRIC-RAILROAD TRACK.

SPECIFICATION forming part of Letters Patent No. 653,970, dated July 17, 1900.

Application filed April 24, 1900. Serial No. 14,106. (No model.)

To all whom it may concern:

Be it known that I, EKKO SOLLMANN, a citizen of the United States, residing at Hoboken, Hudson county, State of New Jersey, have invented certain new and useful Improvements in Electric-Railroad Tracks, of which the following is a specification.

My invention relates to electric-railroad tracks, and has for its object to produce an electric-railroad track especially adapted for use in connection with toy electric railroads, although it is obvious that the invention is capable of other uses.

I will describe herein a track embodying one form of my invention and will point out the characteristic features of my invention in the claims at the end of this specification.

In the drawings, Figure 1 is a sectional side elevation of a rail-joint. Fig. 2 is a transverse section on lines 2 2 of Fig. 1. Fig. 3 is a sectional plan view. Fig. 4 is a detail side view of the coöperating parts of the rail-joint. Fig. 5 is a plan view of several sections of track secured together, and Figs. 6 and 7 are detail views of the cross-ties.

In the drawings, *a* represents a rail, the said rail being hollow and bent up of sheet metal. In the present instance I have shown the rail as consisting of a hollow tread 1, a doubled web 2, and a double base 3, the entire rail being hollow. These rails are suitably mounted on cross-ties *b* and are provided with inwardly-projecting lugs or teats *c*, which are adapted to be engaged by a com-

bined rail or circuit-connector. This combined rail and circuit-connector is shown in the present instance as a rod or pin *d*, pointed at each end and of such size as to enter the hollow tread of the rail and fit firmly therein and make firm contact with the teats *c* or lugs *c*. It is obvious that good electrical and mechanical connection may thereby be effected.

Having described my invention, what I claim, and desire to secure by Letters Patent, is—

1. As a new and useful article of manufacture a railroad-track consisting of rails bent up of sheet metal, having hollow treads and inwardly-projecting teats or lugs, and a double-pointed pin adapted to enter the said treads to form good electrical and mechanical connections.

2. As a new and useful article of manufacture a railroad-rail bent up of sheet metal having a hollow tread and the inwardly-projecting teats or lugs *c* substantially as described.

3. A rail-joint comprised of abutting hollow sheet - metal railroad - rails having inwardly-projecting teats or lugs and the pin *d* entering the hollow portions of the abutting rails and making contact with the teats.

EKKO SOLLMANN.
